UNITED STATES PATENT OFFICE.

WALTER BLEISTEIN, OF KOENIGSWUSTERHAUSEN, GERMANY, ASSIGNEE, BY MESNE ASSIGNMENTS, TO AMERICAN INVESTIGATION CORPORATION, OF NEW YORK, N. Y., A CORPORATION OF MARYLAND.

STATEROOM, DRAWING ROOM, AND SIMILAR COMPARTMENTS.

Application filed February 20, 1922. Serial No. 537,668.

To all whom it may concern:

Be it known that I, WALTER BLEISTEIN, residing at Koenigswusterhausen, Prussia, Germany, have invented certain new and useful Improvements in Staterooms, Drawing Rooms, and Similar Compartments; and I do hereby declare the following to be a full, clear, and exact description of the invention, such as will enable others skilled in the art to which it pertains to make and use the same.

My invention relates to an improvement in staterooms, drawing rooms, or other similar compartments for ships, railway cars, dirigible balloons and other aircraft, and all vehicles for use in the transportation of passengers.

In all ships, railway cars, and aircraft, the great problem to be solved is how to economically arrange for the comfortable accommodation of the passengers in the very limited space provided, and especially is this the case where sleeping accommodations are required to be furnished, and for this reason most of the staterooms or cabins on sea-going ships and the staterooms or drawing rooms on railroad cars, are occupied simultaneously by two or more passengers.

One of the most common and universally used plans, has been to have two berths, upper and lower, in each stateroom or cabin to be used jointly by two persons, and this arrangement has been very unpopular and unsatisfactory in every respect to all concerned, as no one likes to share a room with an unknown person, even for one night, much less for a more extended period on a long journey.

My invention avoids and cures the above disadvantages, without requiring for one person more than half the space occupied by two persons under former conditions.

It has for its object to provide a stateroom or cabin which is adapted for use, both during the day and night and capable of being converted or arranged by suitable partitions so as to provide separate sleeping quarters at night for one or more persons, and also separate individual seats for use in the day time.

It further has for its object to provide a stateroom made to accommodate two persons either jointly or separately during the

day and capable of being divided at night 55 in order to provide two complete individual or separate compartments or rooms with a berth in each room of normal size so that each person may have a berth in a separate apartment.

It finally has for its object to provide a stateroom, cabin, or drawing room of normal arrangement and equipment for two or more persons, which is simple, economical, and durable in construction, and very convenient, comfortable and satisfactory in every respect in use.

The invention consists in the several features and in the construction, combination and arrangement of such features as are 70 more fully hereinafter described and claimed.

Referring to the drawings:—

Fig. 1, is a front elevation of the stateroom arranged for the accommodation of 75 two persons, each having a separate individual compartment and a sleeping berth.

Fig. 2, is a top plan view.

Fig. 3, is a vertical section on the line 3—3 of Figure 2.

Fig. 4, is a front elevation of the stateroom, shown in Figures 1, 2, and 3, as it appears when thrown into a single room with the upper berth folded down and the dividing partition folded.

Fig. 5, is a top plan view of Figure 4.

Fig. 6, is a vertical section taken on the line 6—6 of Figure 5.

Fig. 7, is a front elevation of the stateroom as it appears when it is desired to 90 have the stateroom divided into two separate compartments during the day time.

Fig. 8, is a top plan view of Figure 7.

Fig. 9, is a vertical section on line 9—9 of Figure 8.

Fig. 10, is an elevation of the folding partition.

Fig. 11, is a top plan view of a modified form of my invention for use when the berths are narrower than the usual normal 100 size. Figures 12 and 13 are elevations of the modified forms of the foldable partition.

In the drawings in which similar reference characters denote similar parts throughout the several views, 1 represents a stateroom, drawing room, or cabin arranged in accordance with my invention, which is

2
provided with a floor 2, a top or ceiling 3, and enclosing walls; 4 being the outside wall, 5 the inside wall, and 6 and 7 the front and rear walls, respectively.

5 The inside wall 5 is provided with doors 8 and 9, both hinged thereto, and 10 is a lower berth supported by and preferably secured to the outside wall 4, and 11 is an upper berth hinged to the wall 4, and supported in place by means of bracket 12 pivoted to the rear wall 7, when in use as a sleeping berth, the bracket 12 being adapted to be moved back against the wall 7 allowing the berth 11 to be swung downward, and be folded flat against the inside of the outside wall 4 when not in use in the day time.

6 A foldable partition 13 is provided for use in dividing the stateroom into two separate, distinct or individual compartments 14 and 15, such partitions being hinged to the inner wall 5 at point 16 between the doors 8 and 9.

7 The foldable partition 13, which is of such height as to extend from the floor to the top or ceiling of the stateroom, is provided with an upper foldable section 17, a lower foldable section 18, and intermediate or middle foldable section 19, each of the sections being hinged to the inner edge of the partition by means of suitable hinges 20, and in order to give space to the thickness of the mattress of the upper berth 11, when such berth is folded down and not in use in the day time, the section 19 is provided with a foldable part or filler 19^a which is hinged to the outer edge of section 19. When the upper berth 11, is swung up for use at night, the section or filler 19^a is brought in the same alignment as section 19.

8 It is obvious that such subdivision of section 19 and filler 19^a will not be necessary if the mattress of the upper berth 11 is parted so that both parts leave a space of the thickness of the section 19. In such a case the section 19 will have the size of section 19 and filler 19^a together.

9 In the day time when it is desired to have the stateroom comprise two separate compartments, the upper berth 11 will be folded down and form a back to the lower berth so that it may be used as a seat or sofa, and the foldable partition will be swung outward from the inside wall 5 until it assumes a position midway of the stateroom and at substantially a right angle to the wall 5, the upper, lower, and intermediate sections, 17, 18, 19, will be swung into vertical alignment, the sections 17 and 19 being above the lower berth 10, and the section 18 below the same, thus dividing the stateroom in the middle and the foldable partition and its several sections will be secured in place by means of bolts or any other suitable fastening devices not shown.

10 When it is desired to convert the state-

room into two separate compartments for use at night, each having a berth, the foldable partition is swung to a position at a right angle to the inner wall 5, the foldable section 17 is moved to the left to a position at substantially a right angle to the main portion of the foldable partition 13, and abuts against the stop 21 and the outer front edge of the upper berth 11, closing the foot end of this berth from the compartment 14, the intermediate section 19, and filler 19^a are moved to a position at substantially a right angle to the main portion of the partition 13, and abut against the outer front edge of the lower berth 10, and a stop 22 on the front wall 6, closing the foot end of this lower berth from compartment 15, and the foldable section 18 is moved under the lower berth and in vertical alignment with the sections 17 and 19.

11 By the above arrangement, the person who has compartment 14, will occupy the lower berth 10, and enter and depart by means of the door 8, and the person who has compartment 15, will occupy the upper berth and enter and depart by means of the door 9.

12 When the stateroom is to be used as one room by two or more persons and not divided into compartments, the foldable partition as shown in Figure 5, is folded up against the wall of the stateroom where it is out of the way or removed entirely, and the door 8 only used to enter and depart from the stateroom, the door 9 being blocked by the folded partition.

13 The two spaces 23 under the lower berth, which are formed by the section 18 of the foldable partition, may be very conveniently used to store hand baggage, etc.

14 In the modified form of my invention shown in Figure 11, where the berths are shown as narrower than the usual normal width of berth, the foldable partition 24 is provided with an upper foldable section 25, an intermediate foldable section 26, having a filler 27 hinged to the outer edge, and a lower foldable section 28, all of such foldable sections being made narrower than those shown in Figure 10 in order to accommodate them to the narrowed berths, and in order to compensate or fill up the space when said partition is arranged to provide two separate and distinct compartments, with a separate berth in each, fillers 29 are provided which may be hinged to the front and rear walls of the stateroom as shown, or may be hinged to the outer edges of sections 25, 27.

15 Instead of having the sections 17, 18, and 19 hinged to the partition 13 as shown, they may be made in separate pieces and held in place by any suitable means not shown.

16 In use, a series of staterooms will be preferably arranged side by side, but they may

be arranged in any other desired manner to suit the particular conditions which may arise in installing the same.

I do not wish to be understood as limiting myself to the specific details of constructions and arrangements as herein described and illustrated, as it is manifest that variations and modifications may be made in the features of construction and arrangement, in the adaption of the device to various conditions of use, without departing from the spirit and scope of my invention and improvements. I therefore reserve the right to all such variations and modifications as properly fall within the scope of my invention and the terms of the following claims.

What I claim is:

1. In a stateroom having berths, a foldable partition adapted to divide the said stateroom into a plurality of compartments, said partition having upper and intermediate foldable sections each adapted to abut against one of the berths, and a lower section to divide the space under the lower berth.

2. In a stateroom having berths, a foldable partition hinged to the wall of said stateroom and adapted to divide the said stateroom into a plurality of compartments, and said foldable partition having foldable sections which abut against the front edges of the said berths.

3. In a stateroom having berths, a foldable partition hinged to the wall of said stateroom and adapted to divide the said stateroom into a plurality of compartments, and said foldable partition having foldable sections which close a portion of the front of each of said berths and means for securing the said partition in place.

4. In a stateroom having berths, a hinged vertical partition adapted to divide the stateroom into a plurality of compartments, said partition having foldable sections adapted to be placed at substantially right angles to the said partition and close the front portion of each berth and means for securing the partition in place.

5. In a stateroom having berths, a fold-

able partition having foldable sections which close a portion of the space at the front of each berth and divide the space under one of said berths.

6. In a stateroom having upper and lower berths, a foldable partition having a hinged section adapted to divide the lower berth, a hinged section adapted to divide the space above the said lower berth and means for securing said partition and hinged sections in place.

7. In a stateroom, upper and lower berths, a foldable partition adapted to divide the stateroom into a plurality of compartments, said partition having means for closing a portion of the front of each of the said berths.

8. In a stateroom, upper and lower berths, a hinged partition having hinged means for dividing the lower berth and the space above the lower berth at approximately the center, and closing a portion of the front of each berth and hinged means for dividing the space under the lower berth.

9. In a stateroom having berths, a foldable partition adapted to divide the stateroom into a plurality of compartments, said foldable partition provided with a plurality of sections hinged thereto, and one of said sections provided with a hinged section or filler.

10. In a stateroom having berths, a foldable partition adapted to divide the stateroom into a plurality of compartments, said foldable partition provided with a plurality of sections hinged thereto and a plurality of said sections provided with hinged sections or fillers.

11. In a stateroom having berths, a foldable partition adapted to convert the stateroom into a plurality of separate compartments, each having a separate berth, to close a portion of each berth, and when folded allowing the stateroom to be used as one room.

In testimony whereof I have affixed my signature.

WALTER BLEISTEIN.
